UNITED STATES PATENT OFFICE.

BOYDE H. DYE, OF TIPTON, CALIFORNIA.

ANTIFOULING DEVICE.

Application filed September 28, 1926. Serial No. 138,267.

This invention relates to anti-fouling devices for use with cat-heads and similar devices.

An important object of the invention is to provide a device of this character particularly adapted for use with the cat-heads of well drilling apparatus and which provides a means for positively separating the first wrap of a line passed about the cat-head 10 from subsequent wraps thereof.

As is well known to those familiar with the art, the cat-heads of well drilling apparatus are employed for taking temporary strains and making short lifts or hauls by 15 the use of the drilling apparatus. The shaft upon which the cat-head is disposed is continuously driven and if it is desired that a section of pipe be shifted to the derrick to be added to the string already in the well, 20 a rope is secured to the pipe, giving several turns about the cat-head and an operator tails on the opposite end of the line, with the result that as the cat-head rotates, the pipe is drawn into the derrick. It will be 25 obvious that if, during the rotation of the cat-head, the first wrap overlaps a subsequent wrap, this first wrap is, in effect, secured to the cat-head, with the result that the section of line held by the operator 30 would be wound upon the cat-head and the operator will be rapidly drawn toward the cat-head and possibly, in event he is unable to disentangle himself from the rope, be drawn about the cat-head and maimed or 35 killed. A further and more specific object of the invention is to provide a device of this character which, in addition to separating the first wrap from the remaining wraps, provides at least a partial housing for this 40 wrap, in combination with the cat-head, so that all possibility of an overlapping of the wraps is effectually prevented.

These and other objects I attain by the construction shown in the accompanying 45 drawings, wherein for the purpose of illustration is shown a preferred embodiment of my invention and wherein:—

Figure 1 is a front elevation showing an anti-fouling device constructed in accordance 50 with my invention applied to a cat-head, a line being shown in position;

Figure 2 is a side elevation of the anti-fouling device, the arrow indicating the movement of a rope in application to the 55 cat-head;

Figure 3 is a front elevation of the anti-fouling device detached;

Figure 4 is a fragmentary bottom plan view thereof;

Figures 5, 6 and 7 are sections on the lines 60 5—5, 6—6 and 7—7 of Figure 2.

Referring now more particularly to the drawings, the numeral 10 generally designates a vertical support of a well drilling draw-works. Upon this support is mounted 65 a bearing 11 secured by upper and lower series of bolts 12 and 13. The bearing includes a removable cap held in position by bolts 14. The shaft 10 has secured to the outer end thereof a cat-head comprising a 70 spool 15 having at its ends flanges 16, one of which is arranged adjacent the bearing.

In accordance with my invention, I provide a bracket comprising a vertically extending plate 17 having at its upper and 75 lower ends angular portions 18 and 19 adapted to seat against the front face of the bearing at the upper and lower ends thereof and having slots 19 permitting passage of the upper and lower series of the bolts 12 and 80 13 whereby the bearing is secured to the standard 10 of the draw-works. The front face of the plate 17 confronts the drum 10 and is arcuately curved at 20, so that it may closely fit against the periphery thereof. 85 Adjacent its upper end, the plate 17 is offset in the general direction of the prong, as indicated at 17^a and at the bottom of the notch providing the curved edge 20, the plate 17 has an arcuate extension 21 extending 90 beneath and partially around the drum and providing a continuation of the curved edge 20. The arcuate extension 21 has at its lower end a hooked flange 22, the bill portion 23 of which confronts the adjacent flange 95 16 of the drum. The drum, its flange 16, the hooked flange 23 and arcuate extension 21 thus combine to provide a tubular guide 24 through which the first turn of the rope placed about the cat-head may be directed. 100 The first turn of the rope is passed through this guide and since the offset places the upper end of the plate 17 in such close relation to the flange 16 of the drum that the rope may not pass therethrough, the rope is 105 guided to the outside of the plate and wedged longitudinally of the drum by the offset and this results in subsequent turns thereof engaging with the drum at the opposite side of the arcuate extension 21 and the plate 17 110

from this turn. It will be obvious that the plate and its arcuate extension will serve to effectively separate the various turns of the rope from the first turn and thus prevent 5 any possibility of a locking of this first turn which will result in injury to the workmen.

It will also be obvious that the construction hereinbefore set forth is capable of a certain range of change and modification and 10 I accordingly do not limit myself to such specific structure except as hereinafter claimed.

I claim:—

1. In an anti-fouling device for use with 15 drums having flanged ends, a bar arranged in fixed relation to the axis of the drum and perpendicular to said axis at a point intermediate the ends of the drum, the drum confronting face of the bar closely approaching 20 and conforming to the curvature of the face of the drum throughout a portion of the periphery thereof, said bar intermediate its ends being offset toward the flange a distance such that it coacts with the flange to prevent the passage of a rope end. 25

2. In an anti-fouling device for use with drums having flanged ends, a bar arranged in fixed relation to the axis of the drum and perpendicular to said axis at a point intermediate the ends of the drum, the drum confronting face of the bar closely approaching and conforming to the curvature of the face of the drum throughout a portion of the periphery thereof, said arm having an arcuate extension partially encircling the drum, said bar adjacent the opposite end thereof from said arcuate extension being offset toward the flange a distance such that it coacts with the flange to prevent the passage 40 of a rope end.

3. In an anti-fouling device for use with drums having flanged ends, a bar arranged in fixed relation to the axis of the drum and perpendicular to said axis at a point intermediate the ends of the drum, the drum confronting face of the bar closely approaching and conforming to the curvature of the face of the drum throughout a portion of the periphery thereof, said arm having an arcuate 45 extension partially encircling the drum, said arcuate extension having a flange the terminal portion of which extends into close proximity to the adjacent flange of the drum and combines therewith and with the drum 50 to produce a tubular arcuate passage.

4. The combination with a standard, a bearing carried thereby, a shaft within the bearing and a drum secured to the shaft and having flanges at its ends, a bar having its 55 ends secured to said standard and extending

perpendicularly to the axis of the drum at a point intermediate the ends thereof and adjacent one of said flanges, the drum confronting face of said bar being arcuately curved to conform to the shaping of and extending into proximity to the periphery of said drum, said bar intermediate its ends being offset toward the flange a distance such that it coacts with the flange to prevent the passage of a rope end. 65

5. The combination with a standard, a bearing carried thereby, a shaft within the bearing and a drum secured to the shaft and having flanges at its ends, a bar having its ends secured to said support and extending perpendicularly to the axis of the drum at a point intermediate the ends thereof and adjacent one of said flanges, the drum confronting face of said bar being arcuately curved to conform to the shaping of and extending into proximity to the periphery of said drum, said bar having an arcuate extension partially encircling the drum and having its terminal portion secured to the bearing of the shaft. 70

6. The combination with a standard, a bearing carried thereby, a shaft within the bearing and a drum secured to the shaft and having flanges at its ends, a bar having its ends secured to said support and extending perpendicularly to the axis of the drum at a point intermediate the ends thereof and adjacent one of said flanges, the drum confronting face of said bar being arcuately curved to conform to the shaping of and extending into proximity to the periphery of said drum, said bar having an arcuate extension partially encircling the drum and having its terminal portion secured to the bearing of the shaft, said arcuate extension having a flange 85 the terminal portion of which extends into close proximity to said flange of the drum and combines therewith and with the drum to produce an arcuate tubular passage. 90

7. The combination with a rope drum, of means limiting movement of a rope thereon in one direction and an arm coacting therewith arcuately curved to conform to the peripheral curvature of the drum and closely approaching the same at its inner edge, said arm at one point confronting the said means in such spaced relation thereto as to permit engagement of a rope with the drum periphery therebetween and at a second point approaching said means to an extent preventing the passage of a rope engaged with the drum periphery therebetween. 105

In testimony whereof I hereunto affix my signature.

BOYDE H. DYE.
